[57] CLAIM

The ornamental design for a seat, as shown and described.

DESCRIPTION

FIG. 1 is a front perspective view of a seat showing my design in the form of a sofa; and

FIG. 2 is a side perspective view of the seat of FIG. 1 shown in the form of a loveseat.

The sides of the seat forms not shown are mirror images of the sides shown while the rear surfaces thereof are conventional in appearance.

FIG. 1

FIG. 2
